UNITED STATES PATENT OFFICE.

GEORG H. MAGERSUPPE, OF NEW YORK, N. Y.

LANTERN.

Specification of Letters Patent No. 31,896, dated April 2, 1861.

To all whom it may concern:

Be it known that I, GEORG H. MAGERSUPPE, of the city, county, and State of New York, have invented a new and Improved 5 Portable Lantern; and I do hereby declare that the following is a full, clear, and exact description thereof, reference being had to the annexed drawing, making part of this specification, in which—

10 Figure 1, is a perspective view of the lantern when unfolded or developed. Fig. 2, is a top view of the same in the same position. Fig. 3, is a perspective view of the lantern when in use or ready for use. Fig. 15 4, is a perspective view of the lantern when folded together.

The nature of my invention consists in the construction of a portable lantern capable of being readily folded together to the 20 shape and size of a pocket book.

To enable others skilled in the art to make and use my invention I will proceed to describe its construction and operation.

In the annexed drawing A, represents the 25 glazed front, B, and D, the sides and C, the back of the lantern. These four parts are hinged together by vertical hinges. To the side B, is attached permanently a narrow top H, and a narrow bottom G, and cor- 30 responding with both a narrow side piece K. These three parts (G, H, and K,) form right angles with the side B, and are fixed immovably thereto. A triangular shaped top F, and a similarly shaped bottom E, are 35 hinged to the front A. This movable top F, and bottom E, have tongues corresponding with grooves or sockets e, and a, in the fixed top and bottom H, and G. The top F, contains a round hole for the escape of 40 the gases of combustion and a movable cover J, for the protection of the said hole. The movable bottom E, contains a small candle- stick n, for the reception of the candle. The

hollow back C, contains two movable strips L, which may be turned so as to form the 45 handle of the lamp (as shown in Fig. 4).

When the lantern is not in immediate use the top F, and bottom E, are turned as indicated by the red arrows in Fig. 1, the glazed front A, is then turned into the box formed 50 by H, B, and G, K, and the side D, is turned in an opposite direction until the said box is closed by the ends of D, overlapping the box. When in that shape as shown by Fig. 4, the lantern has the size and form of a 55 pocket book and may be readily borne in the pocket. When it is desired to use the same, the handles L, are turned as shown by the red lines of Fig. 4, the side D, is opened as in Figs. 1, and 2, the top F, and bottom 60 E, are turned as indicated by Fig. 2, in such a manner as to fix their tongues into the respective sockets e, and a, the candle at n, is lighted and the side D, overlapping the glazed front A. The lantern will then present the appearance as in Fig. 3.

The lantern thus described is a useful instrument for patrolmen, watchmen, policemen, soldiers, sailors and others in enabling them to bear the same conveniently in their 70 pockets, when not required for use.

Having thus described my invention and the manner of using the same, what I claim as new and desire to secure by Letters Patent is:

The portable lantern herein described capable of being readily folded into the shape and size of a pocket book in the manner and for the purpose substantially as set forth.

Dated New York January 28, 1861.

GEORG H. MAGERSUPPE.
